UNITED STATES PATENT OFFICE.

GEORGE PHILIP SIMMONS, OF HERKIMER, NEW YORK, ASSIGNEE TO HORROCKS DESK COMPANY, OF HERKIMER, NEW YORK, A CORPORATION OF NEW YORK.

LUBRICATOR.

Application filed August 24, 1920, Serial No. 405,630. Renewed October 7, 1922. Serial No. 593,143.

To all whom it may concern:

Be it known that I, GEORGE P. SIMMONS, a citizen of the United States, residing at Herkimer, in the county of Herkimer and 5 State of New York, have invented certain new and useful Improvements in Lubricators, of which the following is a specification.

This invention relates to lubricators, and 10 particularly to lubricators for attachment to the brasses used in railway car journal boxes. The invention is an improvement on the structure described and claimed in the patent to G. P. and B. M. Simmons, No. 1,122,036, granted December 22, 1914.

In the structure described in that patent a wick, composed of metal and fiber strands, is used to conduct oil from the bottom of the journal box to the journal, at or near the 20 edges of the brass. This wick is supported and confined by a bracket which extends the entire length of the brass and on two sides. In the use of said device it has been found that the life of the wick is limited by the 25 packing and choking of the wick where it contacts with the journal.

I have discovered that this packing and choking is due to a slight rocking of the brass in reverse directions as the journal 30 turns in one or the other direction. This pinches the wick between the journal and the bracket, and limits its oil absorbing quality to such an extent as often to require wicks to be discarded before they are much 35 worn.

I have found that this difficulty can be overcome by so changing the form of the wick-supporting means as to leave the wick free throughout substantially its entire 40 length of contact with the journal, and yet so direct and support the wick that it maintains contact with the journal. To accomplish this result I make use of specially formed brackets arranged in pairs, one at 45 each end of the brass.

The preferred embodiment of the invention is shown in the accompanying drawing, in which,

Fig. 1 is a transverse section on the line 50 1-1 of Fig. 2.

Fig. 2 is a longitudinal vertical section through the journal box at one side of the journal, showing the invention applied.

Fig. 3 is an enlarged fragmentary view 55 showing one bracket attached to a brass.

Fig. 4 is a section on the line 4-4 of Fig. 3.

Fig. 5 is a perspective view of a bracket removed from the brass.

Fig. 6 is a perspective view of a spring 60 lock washer suitable for retaining the attaching screws.

A journal box of usual form is shown at 11, and is provided with the usual lid 12, brass 13 and wedge 14. All these parts may 65 be of any usual construction, and hence may depart from the exact form shown in the drawing.

Fastened to the sides of the brass, near the ends thereof, are four pressed metal clips 70 indicated generally by the numeral 15, two of which are reversed with respect to the other two so as to oppose each other at opposite ends of the brass. The two clips on a side of the brass are therefore symmetrical with respect to a line.

Each clip 15 includes an attaching plate 16, formed with a hole 17 and a dowel pin 18, a wick-confining bow 19, and an eye 20. The lower edge of the eye 20 is reinforced 80 by folding over a part of the metal, as is shown at 21. This gives a rounded edge and avoids chafing of the wick at this point.

The sides of the brass 13 are drilled near its ends to receive the dowels 18, and are 85 drilled and tapped to receive attaching screws 22, which are passed through the holes 16 and are locked by spring washers 23. The clips are so mounted on the brass that the bows 19 on one side of the brass 90 project toward each other.

The wick 24, which may be, and preferably is of the type described and claimed in Patent 1,122,037, granted December 22, 1914, to Simmons and Simmons, is threaded 95 through the eyes 20 and under the bows 19 in the manner clearly shown in the drawings, so that it has portions extending along the journal at each side of the brass, and pendent portions at each end of the brass. 100 This ensures such support for the wick as will hold it in contact with the journal at each side of the brass and throughout the length of the brass, and yet leaves the wick free enough to yield if the brass shifts. The 105 wick-confining bows are long enough to fix the direction of the wick, but are carefully so proportioned as to preclude pinching of the wick between the bow and journal. The eyes 20 are bounded at their sides adjacent 110

the ends of the brass by the reversely curved member 25 of the clip, and this is so proportioned as to deflect the wick just enough to retain it against slipping, without causing it to be sharply bent or mashed where it passes through the clips.

The pendent ends of the wick may extend to and lie in oil in the bottom of the box, or if it is desired to ensure a feed of new oil, the ends of the wick adjacent the end of the journal may be placed in an auxiliary oil reservoir 26, such as is shown in the prior patents above mentioned. Whether the reservoir 26 is, or is not used, the functions 15 of the wick and the clips are the same.

The effect of the use of the wick is to feed the oil at the proper rate to the journal, and to keep the oil fluid regardless of atmospheric temperature. In performing these 20 functions the fibre strands feed the oil, while the metal strands conduct heat from the journal through the body of the wick to the oil in the box. The metal strands also give a desirable stiffness to the wick as a whole, 25 so that between the clips it is held in contact with the journal by its own inherent rigidity.

The dowel 18 may obviously be formed integral with the bracket as seen in Fig. 5, by pressing or drawing, and in practice this 30 will doubtless be advantageous in that it simplifies and cheapens production. Any suitable absorbent wick or feeder may be employed.

Obviously, any known or usual means of 35 attachment may be adopted for the clips, including welding, or casting with the brasses, and the like, the invention residing primarily in the provision of independent brackets or clips at or near opposite ends 40 of the brass, and the manner of attachment being variable at will within the known and usual modes of accomplishing the same.

The provision of separate clips permits 45 the ready equipment of brasses already in use, with my lubricating device or attachment, but where new brasses are to be cast it will be found convenient, and probably economical, to form the same with integral members at the four corners having eyes 50 through which the wick may be led, and by which it will be directly supported and held in contact with the journal from eye to eye, as above indicated. As it is desired to claim specifically the integral construc-

tion as well as the separate clip construction, the wick supports and guides formed integral with the brass are claimed in a separate application, Serial No. 471,699, filed May 23, 1921.

What is claimed is:

1. The combination of a journal box; a brass mounted therein; a journal turning against said brass; a wick composed of fibrous and metallic strands; and clips mounted on the sides of said brass, near the ends thereof, and having eyes with adjacent bowed retaining portions serving to retain the wick in contact with the journal at points intermediate said clips, through the inherent rigidity of the wick.

2. The combination of a journal box; a brass mounted therein; a journal turning against said brass; an absorbent wick; and clips detachably secured to the sides of said brass, near the ends thereof, and having eyes with adjacent bowed retaining portions serving to retain the wick in contact with the journal at points intermediate said clips.

3. The combination of a journal box; a brass mounted therein; a journal turning against said brass; a wick composed of fibrous and metallic strands; and wick retaining clips on the sides of said brass near the ends thereof, said clips having loops of sufficient length to retain the intermediate portion of said wick in contact with said journal by the inherent rigidity of the wick, and having wick deflecting portions serving to deflect the projecting ends of the wick to frictionally retain the wick against movement in the direction of its length.

4. The combination of a journal box; a brass mounted therein; clips rigidly and directly secured to the sides of said brass near the ends thereof and formed with wick-retaining loops; and a wick carried by said clips and by them held in contact with the journal from clip to clip.

5. The combination of a journal box; a brass mounted therein and provided on its sides near the ends thereof with wick-retaining clips; and a wick composed of fibrous and metallic strands, carried by said clips, and by them held in contact with the journal from clip to clip.

In testimony whereof I have signed my name to this specification.

GEORGE PHILIP SIMMONS.
